R. G. COYNER.
HOLDER AND AUTOMATIC LOCK FOR MILK BOTTLES.
APPLICATION FILED OCT. 17, 1913.

1,107,043.

Patented Aug. 11, 1914.

FIG. 1

Arthur J. Fletcher
Mildred Elmer

Robert G. Coyner

UNITED STATES PATENT OFFICE.

ROBERT GRAHAM COYNER, OF CHICAGO, ILLINOIS, ASSIGNOR TO POSITIVE SUPPLY COMPANY, OF DAVENPORT, IOWA.

HOLDER AND AUTOMATIC LOCK FOR MILK-BOTTLES.

1,107,043

Specification of Letters Patent. Patented Aug. 11, 1914.

Application filed October 17, 1913. Serial No. 795,777.

To all whom it may concern:

Be it known that I, ROBERT GRAHAM COYNER, a citizen of the United States, and a resident of Chicago, in the county of Cook 5 and State of Illinois, have invented certain new and useful Improvements in a Holder and Automatic Lock for Milk-Bottles; and I do hereby declare the following to be a full, clear, and exact description of the invention, 10 which will enable others skilled in the art to which it appertains to make and use the same.

My invention relates to a holder and automatic lock for milk bottles, comprehending 15 certain new and useful improvements in receptacles of that type adapted to be placed on the exterior of buildings and so arranged that milk in ordinary glass containers may be readily placed in the holder by the milk- 20 man or tradesman and as readily removed therefrom by the householder or customer.

The primary objects of my invention are to provide a holder and automatic lock for 25 milk bottles so constructed that the insertion of the bottle into the holder automatically locks it and the opening of the door against which one end of the holder is placed releases the lock so that the bottle may be 30 readily removed therefrom, facilitating the convenient delivery of milk in containers and minimizing the liability of it being stolen.

Another object of my invention is to provide a holder and automatic lock for milk 35 bottles so constructed that the bottle is locked therein by the milkman or tradesman without any key manipulation and as easily removed therefrom by the householder or customer without any unlocking 40 inconveniences.

Still another object of the present invention is to provide a holder and automatic lock for milk bottles of simple construction 45 so that it can be manufactured in a strong, substantial and durable manner at a very reasonable cost.

With these and other objects, which may as easily be accomplished, in view my invention consists in certain novel features of 50 construction as hereinafter shown and described and specifically pointed out in the claims.

The accompanying drawings forming a 55 part of this specification, in which similar figures and letters of reference represent like parts throughout the drawing, illus-

trates the preferred embodiment of my invention, and in which—

Figure 1 is a perspective elevation of my invention attached to a door jamb, showing a 60 fragmental portion of a bottle locked therein. Fig. 2 is a longitudinal sectional view, showing the bottle being inserted into the holder. Fig. 3 is a similar view, showing the bottle locked in the holder. Fig. 4 is a similar 65 view, showing the bottle being withdrawn from the holder. Fig. 5 is an end view, showing the locking hinge which comes in contact with the door. Fig. 6 is a bottom plan view on a reduced scale.

My improved holder and automatic lock is preferably constructed of metal or other suitable material in rectangular form and comprises a top portion or plate 10 and side plates 11 and 12 at right angles thereto. 75 These side portions are provided with in-turned flanges 13 and 14 adapted to form a run-way and support for the milk bottle as these flanges engage the flange on the neck of the bottle, as illustrated. An end piece 80 or closing portion 15 is riveted into the device, partially closing its exterior end. At the opposite end of the holder is provided a lock leaf 16, one end of which is hinged or pivoted to the top portion 10 and the opposite end is depended, as illustrated, and provided with an aperture 17, the utility of which will be hereinafter more fully referred to. Pivoted within the rectangular body portion formed by means of the top 85 10 and sides 11 and 12 is a leaf lock plate 18, provided with a downturned flange or claw 19, hereinafter more especially referred to. The leaf or lock plate 18 is pivoted by means of the axial rod 20 which is secured into the side portions 11 and 12 passing through lugs 90 21 on the plate 18; and the leaf is actuated upon its axis by means of the spring 22. Attached to the inner end of leaf or lock plate, or forming an integral part thereof, are lugs 95 23 and 24, having apertures through which operates the locking pin 25, which is actuated by a coil spring 26, which encircles the pin 25 between the lugs 23 and 24 and operates with one end against the lug 24 and the opposite end against a nipple or shank on the pin 25, or the locking pin may be actuated by any other suitable means. This locking pin or plunger 25 has a pin 27 placed 100 through the inner end thereof and extending down through an elongated slot 28 provided in the leaf or lock plate 18 and as illustrated

105 110

in Fig. 5 of the drawing. This pin, the head of which is beveled as shown in Figs. 2 and 3 of the drawing, forms a release lever for the lock, the functions of which will be hereinafter fully described. The lock pin or plunger 25 is adapted to insert itself, by means of the actuating spring 26, into the aperture 17 of the lock leaf 16, as illustrated in Fig. 3 of the drawing; and this operation will be hereinafter more fully referred to.

It is now obvious that in the use of my improved holder and automatic lock for milk bottles adapted to be used primarily for holding and locking milk bottles when constructed according to the foregoing, which is at present the preferred embodiment thereof, it will be secured to the door-jamb A of the back door or other door most conveniently approached by the milkman or tradesman. It is attached by any suitable fastening elements and is so arranged that the inner end comes in contact and rests against the door B when it is closed, fragments of the door and jamb showing the operation of the holder being illustrated in Fig. 1 of the drawing. The fastening elements illustrated consist of screws indicated by C in Figs. 2, 3 and 4 of the drawing. The holder having been attached as above stated and the door closed leaves the locking portion thereof in the position illustrated in Fig. 2 of the drawing. The milkman or tradesman may then readily insert the bottle neck into the device as shown in Fig. 2, which action forces the lock plate 18 into the position which it occupies in Fig. 3 of the drawing, when the spring 26 forces the lock pin or plunger 25 into the aperture 17 in the lock leaf 16, as illustrated, and the bottle is thus automatically locked within the holder, manifestly comprehensible by consulting Fig. 3, and cannot be removed therefrom until the door B is opened inwardly, when the bottle may be readily withdrawn from the holder, as indicated by Fig. 4 of the drawing, leaving the locking device in the position which it occupied before the bottle was inserted into the holder, indicated in Fig. 2 of the drawing, and the holder ready to receive and automatically lock therein another bottle after the door B has been closed against the holder and lock leaf 16. In case the holder should, from any cause or by the act of unauthorized persons, become locked without the placement therein of the bottle, then the milkman or tradesman releases the lock by withdrawing the lock pin or plunger 25 through the instrumentality of the pin 27 depended downwardly through the elongated slot 28 in the leaf or lock plate 18; but it will be readily comprehended by consulting the drawing that this operation of releasing the lock pin cannot be perpetrated when the bottle is locked within the holder as the pin 27 cannot be reached. The down-

wardly extended beveled head of the release pin 27 is of utility in that the pin does not when so constructed retard the ready insertion of the bottle into the device, manifestly comprehensible from Figs. 2, 3 and 4 of the drawing.

The foregoing when taken together and construed in connection with the drawing forming a part of this application manifestly discloses the effectual operation, as above stated, and that a milk bottle or other similar container will be automatically locked within the holder without any further manipulation than the insertion of the neck of an ordinary glass milk container into the holder, as above described, thus obviating the use of keys and other complicated devices requiring much time of the milkman or tradesman, which contrivances are in general unsatisfactory. I do not desire to be understood, however, as limiting the construction of my improved holder and automatic lock for milk bottles to the one illustrated and described, but desire to cover by Letters Patent the general features and reserve the right to vary the construction and arrangement of the essential parts within the limits of mechanical skill and the principle involved and to make the holder of such metal or material and in such adaptable shapes and forms as practice will make manifest are most desirable and efficacious for the uses and purposes for which it is designed.

I am aware that so-called receptacles and holders for milk bottles have been heretofore invented and patented and adapted to receive containers of like character, but as far as I am informed such devices require the utilization of keys and complicated operations consuming much time and occasioning much inconvenience to the milkman or tradesman; and, I am not aware that the novel and essential elements embodied in my present invention, in its preferred construction, have ever been disclosed.

What I claim, therefore, is:

1. A holder and automatic lock for milk bottles comprising a top plate, downwardly appended side portions on said plate, inwardly extending flanges from said side portions forming a run-way for the neck of the bottle, a locking plate pivoted between said side portions, a downwardly appended flange at one end of said locking plate and suitable means for automatically locking said plate in a predetermined position at its opposite end.

2. A holder and automatic lock for milk bottles comprising an open bottomed box-shaped holding device, inwardly disposed flanges forming integral parts of the sides of said box, a centrally pivoted lock plate appended within said box, a downwardly disposed flange on one end of said plate, a

- spring actuated lock-plunger secured to the opposite end of said plate, a lock leaf hinged to the end of said box opposite to the end containing the said downwardly disposed flange of the lock plate, an aperture provided in said lock leaf adapted to receive the said plunger and a spring adapted to downwardly depress the end of said lock plate.
- 10 3. A holder and automatic lock for milk bottles comprising a box-shaped receptacle integrally formed, flanges forming the bottom of said receptacle adapted to constitute a run-way for the bottle neck, a pivoted lock plate operating within said receptacle, a downwardly disposed flange on one end of said plate and suitable locking means at the other end thereof, substantially as specified.
- 15 4. A holder and automatic lock for milk bottles comprising a top plate and integral side plates, inturned flanges on the lower edges of said side plates suitably placed to receive the bottle neck between said flanges, a pivoted spring actuated lock plate operating between said side plates, a downwardly disposed flange on one end of said lock plate,
- a downwardly appended lock leaf hinged to said top plate and a spring actuated locking plunger attached to the end of the said lock plate adjacent to the said lock leaf and adapted to operate in an aperture provided in said leaf, substantially as specified.
- 20 5. A holder and automatic lock for milk bottles comprising a holder formed with a top portion and side portions, inwardly disposed flanges on said side portions, an inclosing portion secured to said side portions and to said top portion at one end thereof, a spring actuated plate operating within the holder formed by said side and top portions, a downwardly disposed flange on one end of said plate, a locking device on the opposite end of said plate and a downwardly appended locking leaf attached to said top portion, substantially as specified.
- 25

In testimony that I claim the foregoing as my own invention I hereunto subscribe my name in the presence of two witnesses.

ROBERT GRAHAM COYNER.
